FIG. 1 is a perspective of a leveling cap for a tile leveling system;

FIG. 2 is a front elevational view of the leveling cap;

FIG. 3 is a right elevational view of the leveling cap;

FIG. 4 is a top plan view of the leveling cap;

FIG. 5 is a rear elevational view of the leveling cap;

FIG. 6 is a left elevational view of the leveling cap; and,

FIG. 7 is a bottom plan view of the leveling cap.

The broken lines in the drawings depict parts of the article that form no part of the claimed design.

1 Claim, 7 Drawing Sheets
